UNITED STATES PATENT OFFICE

GOTTFRIED PAESLER, OF DANZIG, FREE CITY OF DANZIG

GARMENT PRESS

Application filed February 7, 1931, Serial No. 514,206, and in Germany November 5, 1928.

This invention relates to a press for pressing clothes and garments and the like and has for its object, to remove the used working steam after the pressing operation and to accelerate the drying of the clothes without the necessity of long pipe lines for conducting the used steam from the machine and of separate heating elements for producing hot air required for accelerating the drying process.

10 As is known, the mechanical pressing is effected by steaming and at the same time pressing the clothes. It has been found necessary, after the pressing operation, to dry by an air current the clothes treated with the steam, in order to preserve the shape and the character of the clothes. This drying was hitherto mostly effective with air at ordinary room temperature with the use of fans, steam ejectors and other equipments producing suction air. All these devices require a set of pipes for discharging the steam sucked off, which pipes must be carefully and accurately constructed, especially in the case of frequently used steam ejectors, in order not to 25 reduce the suction effect. Later it was proposed to heat the air required for drying, in order to improve and accelerate the drying. For this purpose separate heating devices were provided, heated for example by steam or electric resistances. In all the known machines the press cheeks must be opened for drying the clothes, means being provided by which the heated air in the form of compressed air is made to flow through one of the 30 two press cheeks and the garment resting thereon, thereby drying same, and flows out into the work room. Thus the air in the workroom will become saturated with moisture and, as experience has shown, the furniture and the already pressed clothes hanging in the room will become damaged.

35 The invention has for its object firstly to remove the steam saturated used drying air, without conducting it through a pipe line or without allowing it to pass off into the workroom increasing damage, and secondly to improve the drying operation as regards economy, duration and effect.

40 For this purpose hot air, an ample quantity of which forms on the heat radiating

press cheeks, is, according to the invention, stored in one of the press cheeks, forced back through the steamed clothes by means of a suction device or, according to another form of construction, by compressed air, whilst the 55 press cheeks are still closed. The suction device is preferably constructed as a condensation arrangement, which separates and precipitates the steam particles out of the drying 60 air.

Two embodiments of the invention are illustrated by way of example in the accompanying drawings in which:

Fig. 1 shows diagrammatically one form of construction in side elevation and

Fig. 2 is a similar view of the second form of construction.

Fig. 3 shows a cross section through the lower press cheek.

Fig. 4 is a plan view of a portion of the 70 press cheek.

The steam supply conduits have been omitted, as these are well known.

One of the two press cheeks *c* or *d*, preferably the upper press cheek *c* of the machine, is covered with a hood *b*, which collects and stores the hot air forming above the press cheeks. This hot air is utilized, according to the invention, for drying the cloth in that it is forced back through the clothes after 75 they have been steamed into the lower press cheek *d*, the press cheeks remaining closed. This forcing back of the collected hot air may be effected by sucking from the lower press cheek or by compressed air supplied into the 80 heat chamber *b*.

In the form of construction illustrated in Fig. 1, a water pump *h* driven by an electric motor *m* sucks water from a tank *k* through a pipe *i* and forces it through a pipe *g* into a hydraulic air pump *f*. This latter is thus actuated, sucks the steam from the garment between the lower and upper press cheeks *d* and *c* respectively through a connecting pipe *e* and the lower press cheek *d* 85 and dries the garment by the hot air which follows and is formed above the upper press cheek *c* and stored above same by the hood *b* closed by a valve *a*. This valve *a* may be a suction valve or a cock. The pump *m* is 90 95 100

always started up, when the steaming of the garment has been terminated. The suction valve α then opens under the suction effect or in the case of a cock this cock is opened in order to enable the hot air to be drawn off from the hood b and fresh air to pass in. The discharge of the hot air from the chamber b is effected through passages and ports, which are independent of the steam chambers 10 of the press cheek c . The drying air passes from the garment through holes u in the top surface of the press cheek d into the space in this press cheek d . The hydraulic air pump f conveys the used operating water together 15 with the steam sucked off and precipitated by the water jet of the hydraulic air pump and also the sucked off drying air, through a pipe n into the tank k . The air carried off escapes from this tank k into the room through an 20 aperture in its cover, whereas the water can again be circulated. In order to utilize the slight heating of the operating water, the tank k has a jacket j filled with cooling water. This cooling water, when it has become sufficiently hot, can be employed as required for 25 feeding to the steam developing arrangement.

The collection of the hot drying air can evidently also be effected by means of a jacket 30 on the lower press cheek and on other parts of the machine or pipe line heated by the steam conduit. However the upper press cheek is preferable, in order to provide, by means of the hood b , at the same time a protection against the objectionable radiation 35 of heat from this press cheek.

In the form of construction of the machine illustrated in Fig. 2, the hot air stored above the upper press cheek c is forced back into the garment by compressed air. The compressed air is produced by means of a pump o driven by an electric motor, or as shown in the drawings, wherein this pump is actuated by the opening and closing of the upper 40 press cheek c , the lever p of which is connected to the piston of the pressure pump o by means of a link q . The compressed air is collected in a tank r , communicating with the air pump o through a pipe and a check 45 valve s . A pipe line t leads from the tank r to the hot air chamber b of the upper press cheek, where the compressed air is allowed to enter into the hot air chamber b through a cock u , after the steaming of the garment. 50 The compressed air forces the hot drying air between the steam chambers of the upper press cheek into the garment. The used drying air may be sucked out of the garment by the lower press cheek in a well-known manner. The compressed air pump o acts at the 55 same time as a buffer, when raising the upper press cheek so that it is not necessary to provide special buffers.

I claim:—

60 1. In a garment press, a lower press cheek,

an upper press cheek adapted to move towards and away from said lower press cheek, a hood on said upper press cheek adapted to collect the hot air radiated by said press cheeks, and means for forcing the hot air stored in said hood through the garment after 70 steaming and whilst said cheeks are in closed position.

2. In a garment press, a lower press cheek, an upper press cheek movable towards and 75 away from said lower press cheek, a hood on said upper press cheek adapted to collect the heat radiated by said press cheeks, and a suction device connected to said lower press cheek adapted to suck the hot air stored in 80 said hood of said upper press cheek through the garment whilst said cheeks are in closed position.

3. In a garment press, a lower press cheek, an upper press cheek movable towards and 85 away from said lower press cheek, a hood on said upper press cheek adapted to collect the hot air radiated by said press cheeks, a hydraulic air pump connected to said lower 90 press cheek adapted to suck the hot air from said hood of said upper press cheek, a pipe connecting said lower press cheek to said hydraulic air pump, and means for driving 95 said pump.

4. In a garment press, a lower press cheek, an upper press cheek movable towards and 100 away from said lower press cheek, a hood on said upper press cheek adapted to collect the hot air radiated by said press cheeks, a hydraulic air pump connected to said lower 105 press cheek, a water pump connected to said hydraulic air pump, a drive for said water pump, a water tank, a pipe connecting said tank to said water pump, a return conduit pipe from said hydraulic air pump to said tank adapted to effect a circulation of the water from said tank to said hydraulic air pump and back to said tank, said hydraulic air pump at the same time sucking the hot air collected in said hood of said upper press 110 cheek through the garment into said water tank, the steam being precipitated as water of condensation.

5. In a garment press, a lower press cheek, an upper press cheek movable towards and 115 away from said upper press cheek, a hood on said upper press cheek adapted to collect the hot air radiated by said cheeks, an air tank, a pipe conduit from said tank to said hood of said upper press cheek, and a cock in said 120 pipe conduit adapted to admit compressed air into said hood, said compressed air forcing the hot air stored in said hood through the garment, whilst said cheeks are in closed position.

6. In a garment press, a lower press cheek, an upper press cheek movable towards and away from said lower press cheek, a hood on said upper press cheek adapted to collect the hot air radiated by said cheeks, an air 125 130

5 pump, a piston in said air pump, a piston rod of said piston, a lever on said upper press cheek connected to said piston rod, a tank connected to said air pump, a check valve between said air pump and said tank, a pipe conduit from said tank to said hood of said upper press cheek, a cock in said pipe conduit adapted to allow compressed air to pass into said hood, said air forcing the hot air stored in said hood through the garment into 10 said lower press cheek, and means for conveying from said lower press cheek the hot air pressed through the garment.

In testimony whereof I affix my signature.
